UNITED STATES PATENT OFFICE

2,076,398

AIRCRAFT

John Valentine Carden, Camberley, England

Application April 12, 1935, Serial No. 15,985
In Great Britain April 18, 1934

3 Claims. (Cl. 244—55)

This invention relates to aircraft and more particularly to the kind known as gliders or sailplanes. It is common knowledge that a glider or sailplane although capable of taking advantage of air currents to maintain its height when in the air, cannot rise from the ground without external assistance and in order to give a glider sufficient impetus or flying speed to rise from the ground it is the usual practice either to tow the glider along the ground or to catapult it into the air by means of an elastic rope. If a prolonged flight is desired it is necessary either to launch the glider from a convenient hill or to tow the glider to a suitable height by means of an aeroplane. Such arrangements have the disadvantages that several assistants are required to get the machine air-borne and furthermore should the pilot be unable to maintain his height by soaring, it is often necessary for him to land at some distance from the starting point the machine having then to be towed or otherwise conveyed back to the top of the hill or other starting point before a further flight can be made.

The chief object of the invention is to overcome these disadvantages and to provide a glider or sailplane which is capable of rising from the ground without external assistance but which when in the air will have the same or substantially the same aerodynamic efficiency as a glider or sailplane of normal construction.

A glider or sailplane according to the invention is provided with power propulsion means for enabling it to rise from the ground into the air under its own power, said power propulsion means or a part thereof being movable from its operative position, in which position it would offer considerable air resistance when the machine was in flight, to an inoperative position in which position said power propulsion means offers a reduced or negative air resistance. The power propulsion means preferably takes the form of a small internal combustion engine driving an airscrew, the engine and airscrew preferably being normally contained within the contour of the glider when the latter is in flight, in which position they offer little or no air resistance but adapted to be moved by the pilot into an operative and exposed position for such time as will enable the glider to rise from the ground, or if in flight for such time as will enable the machine to effect a landing at a desired point. Alternatively only a part of the power unit such as the air screw may be retractible, in which case the engine if fixed may either be built into the structure of the glider or if exposed, faired to offer the minimum of air resistance whilst in flight.

In order that the said invention may be clearly understood and readily carried into effect, the same will now be described more fully with ref-

erence to the accompanying drawings which illustrate a preferred embodiment of the invention wherein:

Figure 1 is a fragmentary side elevation of the fuselage of a glider or sailplane showing the power unit in its inoperative or retracted position.

Figure 2 is a similar view showing the power unit in its alternative operative position.

Figure 3 is a rear elevation of Figure 1.

Figure 4 is a rear elevation of Figure 2.

Figure 5 is a part sectional view of the preferred mechanism employed for moving the power unit into its retracted position.

Figure 6 is a transverse section to an enlarged scale on the line A—B in Figure 5.

In the construction of glider or sailplane illustrated the power unit includes a small inverted single cylinder internal combustion engine 1 driving an airscrew 2 arranged behind the wing 3 the wing being supported at its centre by a neck 4 projecting upwardly from the fuselage 5. The engine and its associated airscrew are pivotally connected at the point 6 to the rear spar of the wing or other suitable structural part the engine and airscrew when the latter is in a vertical position being adapted to be moved about the pivotal point from the operative position shown in Figure 2 to the inoperative position shown in Figure 1 in which latter position the airscrew, engine and its associated parts are housed within the fuselage or an upward extension thereof directly behind the neck 4, and in that position offer no air resistance. The trailing edge of the wing is cut away as at 7 to permit of this pivotal movement of the engine, the engine being provided with a cowling 8 which when the engine is in its retracted position fills up the opening in the trailing edge of the wing and constitutes a fairing for the upper part of the fuselage immediately behind the bulkhead 9 as shown in Figure 1. The fairing is completed by closure flaps 10 disposed on opposite sides of the fuselage and each formed in two sections hingedly connected together, the closure flaps being hingedly connected to the edges of the fuselage at 11 and actuated by bell crank levers 12 connected thereto and pivotally connected within the fuselage at the points 13. The closure flaps are adapted to be moved from the position shown in Figures 1 and 3 to the position shown in Figures 2 and 4 and vice versa by the engagement of one of the blades of the airscrew with the extremities of the levers, thereby causing the levers to turn about their pivots and move the closure flaps into the required position. The cowling is provided with an opening 14 for the ingress of air to maintain the engine at the correct temperature, the cowling at its upper end terminating in a small gravity petrol tank 15.

In order to move the airscrew and engine into

60

its retracted position it is essential that the air-screw should be stopped whilst in a vertical position and although this may occur automatically on switching off the ignition due to the tendency 5 for the engine to stop with the piston at its bottom dead centre position (presuming the air-screw to be in line with the crank shaft and crank pin) means may be provided for turning the crank shaft by hand. Such means may take 10 the form of a pawl and ratchet or similar device 16 associated with the end of the crank shaft and actuated by the pilot through the medium of a hand lever 17 situated within the cockpit and a flexible wire or cable 18. The device may also be 15 used for starting the engine from the pilot's seat. Should difficulty be experienced in stopping the air-screw on switching off the ignition or closing the throttle a braking device may be provided operating on the crankshaft or a part associated 20 therewith.

Any suitable means may be employed for moving the engine and its associated air-screw from its retracted position into its operative position and vice versa and in the construction illustrated 25 the engine is adapted to be moved by means of a lifting strut 19 which serves to support the engine in its operative position. The strut 19 is pivotally connected to the engine at the point 20 and is pivotally connected at its lower end to trunnions 21 (see Figure 6) on a traversing nut 22 in screw threaded engagement with a threaded shaft 23. The shaft 23 is rotatably mounted in bearings 24 and 25 carried by the fuselage bulkheads 9 and 26 respectively. The trunnions 21 30 carry rollers 27 running in channel shaped guides 28 also carried by the fuselage bulkheads. The shaft 23 projects at its forward end through the forward bulkhead 26 and carries a chain sprocket wheel 29 rigidly secured thereon, the 35 sprocket wheel 29 being connected by means of a chain 30 with a further sprocket wheel 31 secured to a countershaft 32 connected through the medium of bevel gears 33 with a rotatable handle 34 situated within the cockpit. By turning the 40 handle in the appropriate direction the nut 22 is caused to traverse the shaft 23, the engine and its associated air-screw being thereby moved into the required operative or inoperative position. Any suitable form of engine mounting may be 45 employed such as for example the rods 35 and 36 attached to the lower and upper ends of the engine respectively and serving to support the engine pivotally about the axis or point 6. With the arrangement of engine mounting illustrated 50 however the engine is so mounted that the position of its centre of gravity is substantially unchanged thereby preventing any change occurring in the trim of the machine due to moving the engine from its operative to its inoperative 55 position and vice versa.

It will be apparent from the foregoing description that a glider or sailplane fitted with an auxiliary power unit according to the invention will when once in the air have substantially the aero-dynamic efficiency of a glider or sailplane of normal construction, due to the streamlined contour of the glider being unimpaired when the power unit 12 is in its inoperative position. In order to facilitate the glider rising from the ground the 60 fuselage may be provided with relatively small and light landing wheels instead of the usual skid, the landing wheels if necessary being retractible into the fuselage to decrease still further the air resistance.

75 Instead of the pivotal method of mounting the

power unit, the power unit, or a part thereof, such as, for example the air-screw, may be mounted in any other desired way which will enable it to be slidden or otherwise moved into an inoperative position, in which position it offers a diminished air resistance.

What I claim and desire to secure by Letters Patent of the United States is:—

1. A glider or sailplane having as its sole power propulsion means adapted for use or withdrawal 10 at will an auxiliary power propulsion unit in the upper portion of the fuselage of said glider in the form of a small engine and an air-screw in driving connection therewith, there being a cowling on said engine, said propulsion unit when in its 15 operative position occupying an exposed position upon said upper portion of the fuselage in which it lies outside and above the contour of the structure of the glider, and there being a recess in the upper surface of said fuselage and said cowling, and means for moving and lowering the whole of said propulsion unit into an inoperative withdrawn position in which the air-screw lies within 20 said recess in the upper surface of the fuselage and said cowling, and reduces the entire plane structure substantially to the proportions and outline of a mere glider, there being pivoted flaps on said fuselage for closing said recess.

2. A glider or sailplane having as its sole power propulsion means adapted for use or withdrawal 30 at will an auxiliary power propulsion unit in the upper portion of the fuselage of said glider in the form of a small engine and an air-screw in the form of a small engine and an air-screw in driving connection therewith, said propulsion unit when in its operative position occupying an exposed position upon said upper portion of the fuselage in which it lies outside and above the contour of the structure of the glider, there being a recess in the upper surface of the fuselage of 35 the glider, means for moving and lowering the whole of said propulsion unit into an inoperative withdrawn position in which position the air-screw lies within said recess in said upper surface of the fuselage, a cowling on said engine and there being pivoted flaps on said fuselage for closing said recess, said pivoted flaps and the air 40 propulsion unit in withdrawn position serving to reduce the entire plane structure substantially to the proportions and outline of a mere glider, and means operable by said air-screw to move said flap to and from their operative positions to cover and uncover said recess.

3. A glider or sailplane having as its sole power propulsion means adapted for use or withdrawal 55 at will an auxiliary power propulsion unit in the upper portion of the fuselage of said glider in the form of a small engine and an air-screw in driving connection therewith, there being a cowling on said engine, said propulsion unit when in its operative position occupying an exposed position upon said upper portion of the fuselage in which it lies outside and above the contour of the structure of the glider, and there being a recess in the upper surface of said fuselage and said cowling, and means for moving and lowering the whole of said propulsion unit into an inoperative withdrawn position in which the propulsion 60 unit including the air-screw lies within said recess in the upper surface and within the outline of the fuselage and said cowling, and reduces the entire plane structure substantially to the proportions outline of a mere glider.

JOHN VALENTINE CARDEN. 75
